UNITED STATES PATENT OFFICE.

WINFIELD S. NICHOLS, OF ROCKFORD, ILLINOIS.

RAZOR-BLADE STROPPER.

Application filed October 6, 1921. Serial No. 505,706.

To all whom it may concern:

Be it known that I, WINFIELD S. NICHOLS, a citizen of the United States, having residence in Rockford, in the county of Winnebago and State of Illinois, have invented certain new and useful Improvements in Razor-Blade Stroppers, of which the following is a specification, reference being had to the accompanying drawings, forming a part thereof.

The purpose of this invention is to provide an improved mechanism for sharpening razor blades, particularly such as are used in various types of safety razors and which cannot be conveniently held for stropping in the ordinary way. It consists of various features and elements of construction hereinafter described and shown in the drawings, as indicated by the claims.

20 In the drawings:

Figure 1 is a side elevation of a stropping machine embodying this invention.

Figure 2 is a longitudinal medial section of the same.

25 Figure 3 is a transverse section taken as indicated at line 3—3 on Figure 2.

Figure 4 is a top plan view with certain parts broken away and shown in section.

30 Figure 5 is a detail section of the blade-holding means being taken as indicated at line 5—5 on Figure 4.

Figure 6 is a top plan view of an alternative form of blade-holder designed to receive a single-edged blade.

35 Figure 7 is a side elevation of the blade-holder shown in Figure 6, but with its cylindrical carrier shown in section.

Figure 8 is a detail section taken as indicated at line 8—8 on Figure 7.

40 The machine to which this invention relates, is designed to be used with any common form of flexible leather "strop", being provided with guiding means for the strop such as to permit the machine itself to be reciprocated on the strop, and also having means for automatically reversing the blade at the end of each stroke, or rather at the commencement of each reverse stroke. As shown in Figures 1 and 2, the frame comprises side plates, 1, transversely connected by a cross bar, 2, at the middle of their length and by spacers, 3, at the ends. Directly above the cross bar, 2, is journaled a cylindrical member, 4, with its trunnions, 5, carried in bushings, 6, secured in the side plates, 1. The member, 4, serves to ful-

crum a blade-holder consisting of a carrier plate, 7, rigidly secured in a slot or groove formed in the cylindrical member, 4, and a co-operating clamping plate, 8, overlying the part, 7, in such position that their plane of contact is substantially a radial plane of the cylinder, 4. A blade such as the double-edged wafer blade, 9, is clamped between the plates, 7 and 8, by means of a clamp screw, 10, and a nut, 11, thereon, the screw, 10, being set rigidly in the plate, 7. For accommodating apertured blades such as those of the Gillette type, the clamping plate, 8, is formed with annular protrusions or bosses, 12, which register with the openings in the blade and also with openings in the plate, 7, as indicated in Figure 5. Back of their clamping edges the plates, 7 and 8, are curved apart at 7^a and 8^a, thus providing a channel or clearance space between them which avoids metallic contact of the clamping members with the inner edge of the blade, 9.

45 In the alternative form of clamping device shown in Figures 6, 7 and 8, for a single-edged blade such as that shown at 13 having its unsharpened edge provided with a folded reinforcement, 14, the bend or offset, 7^a, and the corresponding bend or offset, 15^a, of the substitute clamping plate, 15, affords space for accommodating this reinforcement, 14. There being no apertures in this type of blade, it is retained in the holder by means of lugs or clips, 16, bent down 50 at the ends of the clamping plate, 15, overhanging the ends of the blade and the edges of the lower plate, 7.

55 At the ends of the frame there are journaled on the spacing members, 3, a pair of guide rollers, 17, for the strop which is indicated at 18. Midway between these guide rollers there are loosely mounted a pair of friction rollers, 19, preferably made of fibre or similar long-wearing material, and retained in the frame by their reduced ends or trunnions, 20, engaging elongated apertures, 21, in the side plates, 1. The friction rollers, 19, are thus positioned for simultaneous contact with the cylindrical member, 4, and the strop, 18; preferably they are symmetrical with respect to the diametral plane of said cylindrical member, 4, which bisects the angle of swing of the blade-holder. Said friction rollers, 19, are also located so that the strop, 18, in passing over the guide rollers, 17, and under the friction rollers, 19, is de-

flected from a straight-line course; thus when the strop is held under tension there will be a strong frictional engagement between said strop and the rollers, 19, serving 5 to rotate them as the frame is reciprocated upon the strop. Such rotation of the rollers, 19, is transmitted to the cylindrical member, 4, for swinging the blade-holder through its range so as to reverse the blade 10 at the commencement of each stroke and cause it to trail over the strop throughout the remainder of the stroke. The surface of the cylinder, 4, is a smooth metallic surface, preferably of hardened steel so that when 15 the swinging movement of the blade-holder has been effected the rollers, 19, will slip against this smooth surface of the cylinder, 4, and continue their own rotation without any substantial slippage with respect to 20 the strop. Thus the friction rollers, 19, will remain truly cylindrical; if in time they wear down slightly, the play of their trunnions, 20, in the apertures, 21, will still permit operative contact of the rollers, 19, with 25 the cylinder, 4; and the surface of the cylinder, 4, being harder than the friction surfaces of the rollers, 19, will not tend to wear flat at any particular line of contact, but will itself remain substantially a true cylinder and will always respond readily to the 30 turning action of the rollers, 19, at the commencement of each stroke on the strop.

Being loosely retained by the elongated apertures, 21, the rollers, 19, will not strongly 35 engage the cylinder, 4, except when the strop, 18, is held under tension; therefore it is desirable to provide means for holding the sharp edge of the blade in the blade-holder off from the surface of the strop 40 whenever the strop tension is relaxed; otherwise the machine might be slid over the relaxed strop without reversing the blade-holder to trailing position, in which case the blade would cut and injure the strop. This 45 danger is entirely obviated by providing yielding cushion springs, 22, secured by screws, 23, to the side plates, 1, of the frame. These springs are shown as short coils with their ends extending transversely of the 50 frame so as to reach under the radially extending blade-holder and support it normally in the position shown in dotted lines in Figure 2. Each of the coil springs, 22, is wrapped loosely on a flanged drum, 24, 55 which also constitutes the nut of the screw, 23; the inner end of the spring, 22, being fixedly engaged with the drum, 24, it becomes possible to adjust the drum and the spring rotatably so as to bring the extending end of the spring exactly to the position required for holding the blade off from

the strop by a safe distance. As soon as the strop, 18, is drawn taut and the machine is reciprocated upon it, the frictional engagement of the rollers, 19, with the cylindrical member, 4, will turn the latter in opposition to the cushion spring, 22, bringing the blade edge against the strop directly over one of the rollers, 17, with ample force for the desired sharpening action. 70

Any convenient form of handle may be provided for operating the machine upon the strop; for convenience in packing the device, I prefer to make the handle, 25, screw threaded at one end so as to be removable 75 from the cross bar, 2, in which it is fixed for use.

I claim:

1. A blade-stropping machine comprising a frame with a swinging blade-holder fulcrumed thereon, a cylindrical member operatively connected with the blade-holder, a strop guided in the frame and a pair of friction rollers positioned for simultaneous frictional engagement with the cylindrical member and the strop for transmitting rotation to the former to swing the blade-holder on its fulcrum as the frame is reciprocated on the strop. 80

2. In the combination defined in claim 1, said friction rollers being disposed symmetrically with respect to the fulcrum axis at equal distances on opposite sides of a plane which bisects the angle of swing of the holder. 90

3. In a blade-stropping machine adapted to be reciprocated bodily upon a strop supported in a substantially straight line under tension the combination of a frame provided with guides for a strop; a blade-holder mounted in the frame for pivotal motion for carrying a blade to be stropped; a pair of studs mounted in the frame at opposite sides of the pivots of the blade-holder; and torsion-springs mounted on the respective studs and provided with parts for lifting a blade from the strop whenever the strop tension is relaxed. 100

4. The combination, with a strop supported for use in a substantially straight line, of a frame threaded upon the strop for reciprocation thereon, a rocker carrying a blade-holder, and friction-rollers loosely journaled in the frame for actuating the rocker and blade-carrier; the friction-rollers being symmetrically movable toward and from the rocker by reason of said loose journaling. 110

In testimony whereof, I have hereunto set my hand this 3rd day of October, 1921.

WINFIELD S. NICHOLS.
